CLAIM

We claim the ornamental design for a basket for a shopping cart, as shown and described.

DESCRIPTION

FIG. 1 is a perspective view of a basket of a shopping cart showing our new design.

FIG. 2 is a right side view of the basket shown in FIG. 1.

FIG. 3 is a left side view of the basket shown in FIG. 1.

FIG. 4 is a top view of the basket shown in FIG. 1.

FIG. 5 is a front view of the basket shown in FIG. 1.

FIG. 6 is a back view of the basket shown in FIG. 1; and,

FIG. 7 is a perspective view of a shopping cart including the basket shown in FIG. 1.

The bottom views are not a part of the claimed design. Elements shown in broken lines in FIGS. 1-7 are included for the purpose of illustrating portions that form no part of the claimed design.

1 Claim, 7 Drawing Sheets# US D886,404 S
